[57] ABSTRACT

A composite leather button characterized by symmetrical inward and outward laminations having confronting adhesive-coated mating faces adhesively bonded face-to-face. A readily applicable shank is provided and is preferably of a cotter-pin type and is, accordingly, provided at one end with an attaching eye accessibly located beyond the garment confronting face of the inward lamination and is adapted, to be sewed to the garment. Novel means is sandwiched between confronting faces of the laminations and functions, to prevent the laminations from accidentally coming apart and separating under ordinary circumstances and particularly when subjected to agitation, that is, while the button is being dry cleaned and during which time the adhesive media may be undesirably subjected to deleterious chemicals.

LAMINATE LEATHER BUTTON WITH PRONG-TYPE ANCHOR

This invention relates to certain new and useful improvements in composite garment buttons, more particularly, buttons which are made up of aligned face-to-face adhesively bonded inner and outer laminations of leather and wherein the connectible face of the inner lamination is provided with a readily accessible eye which is adapted to be sewed to the garment.

It is prevailing practice to align the confronting interior surfaces of two disc-like leather laminations and to unite the laminations in properly oriented relationship with the aid of pressure responsive adhesive media. In addition, it is common practice to provide the attachable or inner lamination with a shank, more particularly, an adaptation resembling a cotter-pin and provided at one end of the shank proper with an attaching eye and at the other end with outwardly bent detents. The fact that buttons made up of leather are in widespread use it is common practice to provide the display face or surface of the outer lamination with embossments defining an imitation woven leather effect.

Experience has repeatedly shown that the adhesive media which is sandwiched between the laminations is subject to deterioration with a result that the laminations are either wholly or partially separated in a manner that the button is often ruined and unacceptable for approved use. This deleterious action and undesirable result shows up when the garment with the buttons thereon is dry cleaned. This is to say, the deleterious cleaning chemicals act on the bonding adhesive media and allow the laminations to separate. Primarily, separation results, under most circumstances, from the agitation and tumbling of the buttons in the garment cleaning machine.

An object of the present invention is to advance the art in the field of endeavor under consideration through the medium of anchor means which is interposed between the confronting surfaces of the companion laminations. This means coacts with a cooperating end of the associated shank and, more particularly, embodies lateral circumferentially spaced prongs which are capable of being embedded in the coating face portion of the outer lamination and, in so doing, prevents disintegration and separation of the laminations.

Briefly, the herein disclosed composite button is unique in that it is characterized by two disc-like face-to-face laminations of leather one of which is designated as the inner or inward lamination and the other one as the outward or outer lamination. The display face of the outer lamination is preferably convexly shaped and embossed to provide surface ornamentation, more particularly, the desired imitation woven leather effect. The confronting or opposed surfaces of the two laminations are joined by coacting plies of adhesive media which lends itself to acceptable use in this field of endeavor. The axial or central portion of the inner lamination accommodates the shank portion of the overall shank, that is, a cotter-pin-type shank whose protruding outer end is fashioned into an attaching eye, the inner ends of the legs being laterally bent to serve as detents. The stabilizing and anchoring means comprises a simple slotted washer through which a portion of the shank extends in a manner that the ends of the

legs assist in holding the washer in place. The marginal edge of the washer is provided with lateral circumferentially spaced pointed prongs which penetrate and are embedded in the adhesive-coated surface of the outer lamination. When the two laminations are forcibly squeezed together to complete the final assembling step the prongs are clenched and a positive anchoring result is thus assured.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIG. 1 is an exploded perspective view showing the inner and outer laminations of leather and a prong-type anchor and a cooperable eye-equipped shank, these four parts being associated for expedient assembling purposes.

FIG. 2 is a view in perspective showing the essence of the invention, more particularly, the slotted inner leather lamination, washer-like anchor and the associated assembling and penetrating prongs.

FIG. 3 is a view in perspective of the finished button which ties in with FIGS. 1 and 2.

FIG. 4 is an enlarged detail view with parts in section and elevation taken approximately on the plane of the central vertical section line 4—4 of FIG. 3, looking in the direction of the indicating arrows.

Referring to the views of the drawings singly and collectively and with the use of like reference characters indicating like parts, attention is first directed to FIG. 1. Here it will be evident that the first or inner (or inward) leather lamination is denoted by the numeral 6, the same being of flat-faced disc-like construction. The interior flat or planar surface is denoted at 8 and the endless marginal or peripheral edge at 10. The central or hub portion is provided with an elongated slot 12 which opens through the interior and exterior surfaces. The exterior surface is shown at 14 in FIG. 4. In actual practice and as a finishing step this surface is suitably finished and impressed to provide a pressed portion surrounded by an encircling rib-like bead 16. Thus, the so-called inner lamination 6 is characterized by interior and exterior surfaces, an encompassing peripheral edge and a slot 12 at the center to accommodate the component part which is hereinafter referred to as the shank and which is denoted, as an entity (see FIG. 1) by the numeral 18. More specifically, this prefabricated readily insertable shank resembles, a cotter-pin in that it is made from a length of bendable stout wire stock and is fashioned into an eye 20 at one end, the shank proper as at 22. The legs, which make up the shank, are provided with coaxial outstanding limit-stops or detents 24. The locale and functioning of this shank is evident upon considering FIG. 1 at the left and then FIG. 2 wherein the shank has been passed through the slot means provided therefor.

The shank also serves to cooperate with and position and partly retain the aforementioned "means" which is oriented and cooperable with the laminations and which functions effectually in guarding against and virtually preventing the laminations from accidentally parting and separating. More specifically, this means,

denoted generally at 26, comprises a simple flat metal washer 28 which as a central slot 30 which is aligned with the slot 12 when in use. The encompassing marginal edge of the washer is provided with circumferentially spaced laterally projecting triangular or V-shaped prongs 32 whose pointed apical ends are adapted to penetrate the interior planar surface 34 of the outward (outer) disc-like leather lamination 36. This lamination 36 is of a shape and size that it coordinates with the first named or inner lamination 6. There is no aperture in this lamination. On the other hand it has a flat or planar exterior surface 38 which is parallel to the aforementioned interior surface 34. The peripheral or marginal edge is denoted at 40 and this edge is flush with the edge 10 when the two laminations are assembled, as brought out in FIGS. 3 and 4. The interior surfaces 8 and 34 are coated with adhesive material which in practice is interposed or sandwiched between the coating surfaces as denoted at 42 in the finished product shown in FIG. 4. Ordinarily and with regular use the two laminations are properly lined up and stay put. When however this type of composite button is subjected to agitation during the course of dry cleaning, the adhesive media is acted upon and in many instances is so affected that the laminations sooner or later part and render the button substantially useless. By using the pronged safeguarding anchor 26 this objectional result is overcome. It follows that the centrally apertured washer 28 is superimposed upon the adhesive side of the lamination 6. When the slot 30 is lined up with the slot 12 the eye-equipped end of the prefabricated rigid shank 18 is inserted and passed through said slots 30 and 12, the eye 20 protrudes to provide its button mounting or attaching position as brought out in FIGS. 3 and 4. Also the aforementioned lateral dentend 24 assist in positioning and anchoring the pronged washer, as is evident in FIG. 2. It follows that when the lamination 36 is lined up with the companion lamination 6 is firmly pressed in place the pointed prongs 32 penetrate and embed themselves in the lamination as brought out in FIG. 4. In fact during the squeezing and compressing stage the prongs 32 are actually deflected and clenched in the manner shown in FIG. 4 to insure the reliable assembling anchoring result desired.

The manner in which the exposed surfaces of the laminations are finished will vary. Ordinarily the surface 14 is depressed and provided with an encompassing bead 16 as brought out in FIG. 4. On the other hand the display surface of the outer lamination 36 is embossed as designated at 44 to achieve the aforementioned imitation woven leather effect. The fact that surface ornamentation is variable, it will be evident that the manner in which the surface 44 is convexly formed and finished is not limiting.

It is submitted that an analytical consideration of the individual component parts as illustrated in FIG. 1, the manner in which the components 6, 18 and 26 are assembled as shown in FIG. 2 and the nature of the end product and improved result (FIGS. 3 and 4) will be clear from the illustrative drawings. Accordingly, a more extended description is believed to be unnecessary.

The foregoing is considered as illustrative only of the principles of the invention. Further, since numerous

modifications and changes will readily occur to those skilled in the art, it is not desired to limit the invention to the exact construction and operation shown and described, and accordingly all suitable modifications and equivalents may be resorted to, falling within the scope of the invention.

What is claimed as new is as follows:

1. A laminated garment button embodying an inward leather lamination provided at an axially centered area with a slot for passage of a rigid prefabricated shank, said lamination having interior and exterior planar faces, said interior face being coated with pressure responsive adhesive media, an anchor comprising a rigid flat-faced washer centrally superimposed upon said interior face and having a shank slot aligned with said first named slot, a readily applicable shank having a button attaching eye at one end and outbent limit stop detents at the other end, said shank passing through the respective slots with said eye projecting beyond said exterior face, said detents abutting and positioning said washer in a given functioning locale, said washer having penetrating and anchoring means, and, in combination, an outward leather lamination like and complementary to said inward lamination and opposed to and functionally mated with said inward lamination and also having interior and exterior planar faces, the interior face being coated with pressure responsive adhesive media and being pressed against and bonded to the adhesive coated face on said inward lamination, said anchoring means comprising prongs on said washer and said prongs being forcibly embedded in the interior face of said outward lamination and securely clamping said laminations together.

2. The laminated garment button defined in and according to claim 1, and wherein the aforementioned penetrating and anchoring means comprises circumferentially spaced laterally projecting pointed prongs provided on the marginal edge of said washer and which are embedded when in use and deflected and clenched in their given embedded positions.

3. The laminated garment button defined in and according to claim 2, and wherein the exterior surface of the inner lamination is depressed in a manner to define an encompassing outstanding bead, and wherein an exterior display surface of the outer lamination is formed convexly and is embossed in a manner to provide an imitation woven leather finish.

4. A laminated button for use on garments and apparel comprising like inward and outward complementary laminations having inward confronting and mating faces coated with adhesive media and pressed together in face-to-face relationship and retentively united, an axially positioned rigid shank secured to the adhesive coated face of said inward lamination, said shank having a button attaching eye projecting axially and accessibly beyond the garment confronting exterior surface of said inward lamination, and means oriented and cooperable with said laminations in a manner to effectively guard against and prevent said laminations from accidentally parting and separating, said means being interposed and centrally sandwiched between said adhesive coated faces and being highly effective when, for example, the button mounted on a garment is subjected to agitation when said garment is being dry cleaned, said laminations being made of firm leather, and said

means comprising an anchor, more particularly, a centered washer having laterally bent marginal anchoring prongs, said prongs being V-shaped and having apical penetrating points which are embedded and clenched in retentive positions in the coacting inward adhesive coated face of said outer lamination.

5. The button defined in and according to claim 4, and wherein the outer display face of the outer lamination is convexly embossed to provide an ornamental woven leather finish.
